UNITED STATES PATENT OFFICE.

RECTOR EGELAND, OF CHICAGO, ILLINOIS.

PROCESS AND APPARATUS FOR CRACKING HYDROCARBONS.

Application filed October 17, 1921. Serial No. 508,286.

To all whom it may concern:

Be it known that I, RECTOR EGELAND, citizen of the United States, residing at Chicago, in the county of Cook and State 5 of Illinois, have invented a certain new and useful Improvement in Processes and Apparatus for Cracking Hydrocarbons, of which the following is a full, clear, concise, and exact description, reference being had to the 10 accompanying drawings, forming a part of this specification.

The invention relates to a process and apparatus for cracking hydrocarbons of a heavy character, such as petroleum, and the 15 extraction or separation therefrom of lighter hydrocarbons, such as gasoline.

The invention has among its various objects the construction of an apparatus and the provision of a process in which crude 20 oil to be cracked is continuously fed under pressure to the apparatus and lighter hydrocarbons are continuously extracted therefrom.

It has been found by many experimenters 25 in the art of cracking hydrocarbons that a pressure of 60 to 150 pounds in the system and temperatures varying from 600 to 1,000 degrees will produce the greatest yield of lighter hydrocarbons. With this amount of 30 pressure and with this degree of temperature employed, it has also been found that the percentage of olefines in the distillate produced from petroleum of the paraffin series is reduced. This is an objectionable 35 ingredient in the distillate, although a small percentage is allowable. It is an object of the invention to provide an apparatus and a process which will efficiently operate with the proper pressures and temperatures to 40 extract and yield the greatest amount of the lighter hydrocarbons at a maximum rate consistent with good quality, for the longest period of continuous operation.

Another object of the invention is to continuously feed to the apparatus a non-condensable gas, preferably a cold gas, or a 45 non-superheated gas, such as methane gas, at a temperature of 50 degrees to 150 degrees Fahrenheit. The non-condensable gas 50 which is a product of the cracking operation of the invention is one of the gases which may be used. It may be led from the receiving tank or other container of the system, or it may be piped from any other 55 source of supply. This gas is introduced

into the supply of crude oil before the crude oil reaches an ejector which is included in the pipe line leading to the heater of the apparatus, which ejector is provided with restricted passages for the flow and propulsion of the fluids. 60

It is a further object of the invention to cause the crude oil which is to be distilled and gas, both of which are under pressure, to mix prior to their entry into the ejector, 65 to enter the ejector and be ejected thereby into the heating area of the apparatus and continue under pressure into other parts of the system. In the heater the high temperatures obtained, combined with the motion, agitation and ebulliency of the mixture of the volatile fluid and the rapidly 70 expanding non-superheated and non-condensable gas of the temperature named fed through the ejector and also the impulse of 75 the newly created gas in the heat area formed by the admixture of the heated crude oil and the gas, not only because of the initial pressure but because of the pressure 80 and the lifting action of the ejector (which may be likened to the action of an air lift), causes the cracking of a large quantity of 85 hydrocarbons in a short time and produces a great quantity or yield of high grade distillate or lighter hydrocarbons. The cracking process is speeded up to a high degree 90 by the inclusion of the ejector in the line and because of the action of the heat on the non-superheated gas fed through the ejector into the heater area. Not only is there increased velocity and action of the liquid and 95 resulting vapors in the heater area and beyond in the apparatus, but the deposition of coke on the heating surfaces is reduced to a minimum and the time of operation of the entire apparatus is extended. 95

It is an object of the invention to lessen as much as possible the deposition of coke on the heating surfaces. Coke forming on the heating surfaces presents one of the 100 greatest dangers in cracking processes, because it weakens the steel at the heating surfaces by combination, frequently causing a local overheating and bursting. The heated gases will thereupon escape and produce one of the most intense and destructive flames possible to produce.

It is another object of the invention to employ vertical oil heating surfaces, in conjunction with other features of the inven- 110

tion, to further reduce the deposition of coke on the oil heating surfaces of the system, as it has been found that there is considerably less deposition of coke on vertical 5 than on horizontal heating surfaces.

It is also an object of the invention to provide a circulatory supply of partially refined crude oil and also a supply of crude oil which is auxiliary to the main continuous 10 supply of crude oil.

A further object of the invention is to provide means whereby the crude oil and the non-condensable and non-superheated gas, such as methane gas, may be separately 15 introduced into the system or only one may be introduced.

In addition to the usual precautions taken in systems like the herein described, it is an object to provide the system with an auxiliary safety device which is operable to relieve the system in any emergency, as when the maximum operating pressure is exceeded, should this occur at any time, and thus minimizing one of the great dangers 20 that is encountered in the practice of a process such as is herein described.

In the particular embodiment of the invention illustrated in the drawings, the use of an ejector is contemplated. A number of 25 pipes or pipe lines are connected to the ejector. One of these pipes is in communication with a source of crude oil supply. Another pipe leads from a source of gas supply to the ejector, the gas being preferably 30 of a non-condensable character, such as hydrogen gas, and preferably not under heat, or superheated, and at a temperature of 50 degrees to 150 degrees Fahrenheit. This gas may be methane gas found in the 35 receiver used in the system. These two pipe connections, that is, the crude oil supply and the gas supply, are connected together so that they will preferably simultaneously and under pressure, feed through the ejector 40 an admixture of oil and gas to the system during the entire operation of the system. Another crude oil pipe is also connected to the ejector, and this provides a means for initially charging the system with the hydrocarbons to be cracked. Two additional 45 pipes or branches are connected to the ejector, one of which leads to the bottom of the still, affording a passage for the unvaporized oil which is to be returned to the ejector 50 and thence to the system, and the other of which leads to vertically arranged heater pipes through which the admixture of crude oil and gas is passed, and subjected to heat. This application of heat causes the gas to 55 expand and the necessary additional pressure to be supplied to change a portion of this mixture into vapors. A different gas, or newly created gas, is formed by the combination of the heated oil and the non-condensable gas. The vapors and the unvapor-

ized heavy oil pass from the heater to a still, from which the vapors escape into a dephlegmator. A portion of the residue passes through the pipe extending from the bottom of the still and back into the system. A crude oil supply pipe is connected to the dephlegmator, and the latter, through a suitable connection with the still, permits the crude oil which is introduced into the dephlegmator and the unvaporized distillates to be passed back into the still. From the still the crude oil from the dephlegmator and the partially refined distillates are passed through the pipe connection between the still and the ejector, at which time this uncracked portion of the oil is again mixed with fresh crude oil and gas, which is again passed through the heater, still and dephlegmator. The vapors which pass from the still into the dephlegmator are, as before stated, separated in the dephlegmator. Those containing the constituents of the lighter hydrocarbons pass into a condenser, which transforms the vapor into a liquid which passes into a receiver, from which the gasoline or lighter hydrocarbons may be drawn for storage or use. 60

Another connection is provided to draw off the tar and less valuable distillates which find their way into and settle to the bottom of the still after portions of the crude oil have been cracked and separated. The still is provided with a blow-off valve to insure safety of operation, and in addition an added safety device is provided in the form of a blow-out plug which, when an excessive pressure exists in the system, operates to relieve it and thereby prevents an explosion. 65

A pressure indicator is employed and preferably associated with the receiving tank into which the distillate is passed. This is provided to indicate the pressure in the system, which may be reduced by the operation of a relief valve provided for the purpose. 100

The operation of the process is as follows: The system is initially charged with crude oil, which fills the heater pipes and partially fills the still and the pipe leading from the still to the ejector. This source of supply is then turned off. When the system is thus filled, heat is applied to the heater pipes and at the proper time the admixture of gas and the constant supply of crude oil is fed through the ejector to the system, giving impulse to the liquid of the initial charge. This liquid, under impulse, upon reaching the heater, gains in velocity and the mixture gains in volume as it is heated, adding to the motion, which serves the dual purpose of adding impetus to the liquid and increasing the volume of the gases, including the newly created gas, which expands and creates pressure, which carries the vapors into the still and other 110

elements of the system, whereby the lighter hydrocarbons may be removed. This operation is continued until all of the lighter hydrocarbons are removed from the crude oil with which the system was initially charged, and subsequently fed to the system during its operation.

The invention will be further explained and more readily understood when read in conjunction with the accompanying drawings, which illustrate one embodiment of the invention, it being obvious, however, that changes and modifications may be employed without departing from the spirit 15 of the appended claims forming a part hereof.

In the drawings,

Figure 1 is a central section of a heater having the various elements entering into 20 the invention associated for cooperation therewith;

Fig. 2 is a plan view of the structure shown in Fig. 1;

Fig. 3 is a sectional view of one type of 25 ejector which may be employed in the structure;

Fig. 4 is a sectional view of a fragment 30 of the piping system showing a pressure relief element employed; and

Fig. 5 is a front elevation of the element employed in Fig. 4.

The ejector hereinbefore referred to is indicated at 10 and clearly shown in Fig. 3, and has provision for the connection of an 35 initial crude oil supply pipe 11 through which the entire system is initially filled or charged with the hydrocarbons to be separated or cracked. This pipe 11 is provided with a valve 12 for controlling the flow of 40 oil to and from the system. The ejector casing has a horizontally arranged pipe 13 connected to it. The opposite end of this pipe 13 is connected to a lower manifold 14, to which are connected a plurality of headers 15, which carry the vertical risers or pipes 16, which terminate at their upper ends in a connection with headers 17, which in turn connect with the upper manifold 18. A pipe connection 19 leads from the 45 upper manifold 18 to the tank or still 20. A vertically arranged pipe 21 extends into the still 20 and between the still 20 and the casing of the ejector 10 and provides a passage between the still and the ejector. Thus it can readily be seen that when the valve 50 12 is opened, the circulatory system, including the pipe 13, lower manifold 14, headers 15, vertical pipes 16, headers 17, upper manifold 18, pipe 19, still 20 and pipe 21 will 55 be filled to the desired capacity, and, after the valve 12 is closed and heat applied, the vaporization of the oil will cause the initial charge of oil to be circulated through the various elements named. The still is filled 60 to such a level that there is provided suffi-

cient space above the level of the liquid so that sufficient vaporization space is furnished. This level of the liquid in the still is approximately maintained by replenishments of fresh crude oil during subsequent 70 operation of the system.

After the initial charge of crude oil is introduced into the system, non-condensable unheated or non-superheated gas, such as 75 methane gas, with a temperature of 50 degrees to 150 degrees Fahrenheit, under pressure, which is secured from a suitable source of supply, is also introduced into the system. Heat is then applied to the riser tubes or pipes 16 by means of the ignition 80 of the gas emitted from the plurality of burners 22, which direct the flames toward these pipes. Solid fuel may be used instead of gas. Grate bars are shown at 23 and an ash pit with an opening at 24. The temperature in the heater is brought up to and maintained at from 600 degrees to 1,500 degrees Fahrenheit. Flame deflecting plates 85 25, 26 and 27 are employed to cause the circulation of the products of combustion 90 around these heater pipes before the products of combustion are permitted to escape through the passage 28 and out through the smokestack 29. The various sets of heater pipes 16 are supported at their upper ends 95 by means of the transversely arranged rods or pipes 30, which are arranged between the vertical pipes and below the headers 17 and rest upon the walls of the furnace 31. The passage 28 is controlled by means of the 100 valve or damper 32. Each of the headers 15 and 17 are provided with apertures which are in alignment with the various pipes 16 and are closed by means of screw-threaded plugs designated 33 and 34, respectively, 105 which are removable to allow these pipes to be cleaned. A cleaning pit 35 with an opening 36 is shown beneath the manifolds and heater risers. A pipe 37 is connected to the lower manifold 14, but the passage of 110 oil, etc., therefrom is prevented by means of the disk 38 which is provided with an annular recess 39. The material of this recess connects the smaller disk-shaped portion 40 with the main disk 38. The material surrounding the smaller disk is of sufficient 115 strength to withstand the ordinary pressures existing in the system (60 to 150 lbs.) and is designed to permit the smaller portion 40 to be sheared or severed from the main portion, thus completing the passage 120 which relieves the pressure in the system, should an excessive pressure be created or exist therein.

As before stated, the ejector 10 is provided with a combined gas and crude oil inlet passage indicated at 41, whereby a mixture of gas and crude oil is constantly fed to the system during its operation, at from 60 lbs. to 250 lbs. pressure. The gas sup-

plying pipe for the inlet passage is indicated at 42 and is provided with a regulating and control valve 43. The crude oil supply pipe 44 having the regulating and control valve 45, is connected to the inlet pipe 41 between the gas regulating valve 43 and the ejector 10, and thus the oil and gas will thoroughly commingle and mix before it enters the pipe 13 through the combined inlet passage 41 and the ejector 10. The gas passage 42 may receive its supply from the receiver 46, or may, if so desired, be fed from any other source. A pipe 47 is shown extending from the receiver 46 to the gas pipe line 42. On each side of the connection between the pipes 42 and 47 are the gas passage control valves 48 and 49. The valve 49 is placed in an additional pipe line 50 through which any excess supply of gas from the receiver 46 may flow. Another gas pipe line 51, provided with a control valve 52, is connected to the pipe 42 between the control valves 43 and 48. The gas pipe line 42 is connected with the pump 53 to furnish the requisite pressure for the gas which is continuously fed to the system. A pump (not shown) is also included in the crude oil pipe line 44 to supply the requisite pressure for the crude oil which is fed to the system. The outlet of the combined gas and crude oil passage 41, or its connection with the ejector 10, is preferably in alignment with the apertured nipple 54 and the restricted passages or Venturi tubes 55 and 56 of the ejector, so that the velocity of the oil and gas entering therethrough will be increased.

From the foregoing description of the structure it is evident that after the introduction of the initial charge of crude oil and gas into the system and the application of from 600 to 1,500 degrees Fahrenheit of temperature thereto in the heater, that this oil and gas will become heated and will circulate, under a pressure of from 60 lbs. to 150 lbs., through the system, and by the gas and oil connections with the ejector, that fresh undistilled crude and uncracked oil and gas will be continuously fed thereto. The vapors and unvaporized heavy oil of this heated admixture of gas and crude oil is passed from the heaters through the pipe 19 to the still 20 and the vapor will thence pass therefrom through the pipe connection 57 into the dephlegmator 58 to which is supplied a quantity of fresh crude oil through the pipe connection 59. The addition of crude oil to the vapor entering the dephlegmator condenses the heavy hydrocarbons allowing the lighter hydrocarbons to escape through the pipe connections 60 to the condenser 61. Pipe connections 62, which may be extended to a point below the liquid level in the still 20 and the opening and closing 65 of which may be regulated by a suitable valve, and which may be of a size found by experiment to maintain a desired liquid level, will allow the condensed heavy hydrocarbons to return from the dephlegmator 58 to the still 20 through the system, and commingle with the fresh crude oil and gas continuously fed to the ejector, to have any values contained therein removed therefrom. The heavy hydrocarbons, tar, waste matter and other substances which have had the lighter hydrocarbons extracted therefrom, remain in the still and may be drawn off through the pipe connection 63, which is controlled by the valve 64. The condenser 61 provided with the cooling fluid inlet connection 65 and the cooling fluid outlet connection 66, is connected at 67 to the receiver 46, into which the distillate or lighter condensed hydrocarbons flow and are stored, and may be drawn off as occasion demands, through the outlet pipe 68 controlled by a valve 69. A high pressure gas relief line 70, with a relief valve 71 and a pressure gage 72, is also connected to the receiver 46. The still is provided with the usual safety blow-off valve 73.

Having thus described the invention, what I claim and desire to secure by Letters Patent is:—

1. The process of cracking hydrocarbons consisting of circulating hydrocarbons, supplying a gas to said hydrocarbons during circulation, subjecting the hydrocarbons and gas to heat, passing the vaporized and unvaporized hydrocarbons resulting from the application of heat to said hydrocarbons and gas to a still and supplying additional gas and hydrocarbons through an ejector to the unvaporized hydrocarbons and again subjecting the unvaporized hydrocarbons, added gas and added hydrocarbons to heat. 95
2. The process of cracking hydrocarbons consisting of circulating hydrocarbons, supplying a gas to said hydrocarbons during circulation, subjecting the hydrocarbons and gas to heat, passing the vaporized and unvaporized hydrocarbons resulting from the application of heat to said hydrocarbons and gas to a still, passing said vapor to a dephlegmator and to a condenser, and supplying additional gas and hydrocarbons through an ejector to the unvaporized hydrocarbons and again subjecting the unvaporized hydrocarbons, added gas and added hydrocarbons to heat. 105
3. The process of cracking hydrocarbons consisting of circulating hydrocarbons, supplying a non-condensable gas to said hydrocarbons during circulation, subjecting the hydrocarbons and gas to heat, passing the vaporized and unvaporized hydrocarbons resulting from the application of heat to said hydrocarbons and gas to a still, and supplying additional gas and hydrocarbons through an ejector to the unvaporized hydrocarbons 115

and again subjecting the unvaporized hydrocarbons, added gas and added hydrocarbons to heat.

4. The process of cracking hydrocarbons consisting of circulating hydrocarbons through a heater, supplying a non-condensable gas under pressure to said hydrocarbons by means of an ejector at the point where circulation is started through the heater, subjecting the hydrocarbons and gas to heat, passing the vaporized and unvaporized hydrocarbons resulting from the application of heat to said hydrocarbons and gas to a still and supplying additional gas and hydrocarbons through the ejector to the unvaporized hydrocarbons, and again subjecting the unvaporized hydrocarbons, added gas and added hydrocarbons to heat.
5. In an apparatus for cracking hydrocarbons, the combination of a heating element and an ejector, said ejector having a passage-way therethrough for the flow in a continuous path of hydrocarbons and gas, said passage-way having a Venturi tube, passages from the ejector to the heating ele-
- ment and from the heating element to the ejector through which the hydrocarbons may circulate, a gas connection into the ejector whereby gas may be fed to the hydrocarbons to be cracked during the circulation through said passages.
6. In an apparatus for cracking hydrocarbons, the combination of a heating element and an ejector, said ejector having a passage-way for the flow in a continuous path of hydrocarbons and gas, said passage-way having a plurality of Venturi tubes therein in axial alignment with each other, passages from the ejector to the heating element and from the heating element to the ejector through which the hydrocarbons may circulate, a gas connection into the ejector whereby gas may be fed to the hydrocarbons to be cracked during the circulation through said passages.

In witness whereof, I hereunto subscribe my name this 14th day of October A. D., 1921.

RECTOR EGELAND.
